MECHANICAL JUMPING STICK

Richard J. Mays, Tacoma, Wash.

Application February 7, 1947, Serial No. 727,691

8 Claims. (Cl. 189—8)

1

This invention relates to improvements in mechanical "Pogo" sticks.

An object of the invention is to provide an improved mechanically operated "Pogo" stick.

Another object of the invention is to provide an improved gasoline engine operated "Pogo" stick.

A further object of the invention is to provide an improved manually controlled gasoline engine operated "Pogo" stick.

A still further object of the invention is to provide a manually controlled variable speed gasoline engine operated "Pogo" stick.

Another object of the invention is to provide an improved manually controlled gasoline engine operated jumping stick which will be highly efficient and enjoyable in operation, and relatively inexpensive to manufacture and produce.

Other objects will appear as the description proceeds.

In the accompanying drawings which form a part of this application,

Figure 1 is a vertical sectional view through the improved gasoline engine operated "Pogo" stick;

Figure 2 is a partial sectional view taken on the line 2—2 of Figure 1;

Figure 3 is a sectional view taken on the line 3—3 of Figure 1; and

Figure 4 is a sectional view taken on the line 4—4 of Figure 1.

Like characters of reference are used throughout the following specification and the accompanying drawings to designate corresponding parts.

In carrying out the invention, there is provided an improved gasoline engine operated jumping stick generally designated by the reference numeral 1 having a rigid upper structure or section including an elongated stick portion 2 formed with a cross handle 3 extending transversely of and adjacent the upper end of said stick portion, said stick portion being preferably formed of metal and having its lower end reduced and threaded as at 4 to extend through a central aperture 5 formed through the cylinder head 6 of the single cylinder 7 of the gasoline engine used for operating the jumping stick.

The cylinder or body section 7 is provided at its upper end with the inwardly extending annular flange 8 for receiving the bolts 9 extending therethrough and through said cylinder head 6, being secured in fixed position by means of the nuts 10 disposed on the threaded upper ends of said bolts 9.

2

A transversely extending foot supporting bar 11 is mounted upon the upper surface of the cylinder head 6 and extends beyond the opposite sides thereof, and is secured in place by the reduced threaded end 4 of the stick portion 2 extending through it, as clearly illustrated in Figure 1 of the drawings.

A spark plug 12 is adapted to be received in the threaded opening 13 in the upper end of the cylinder 7, and is adapted to be connected by means of the electricity conducting wire or conductor 14, with the ignition coil 15 and dry cell battery 16 supported upon the lower surface of the closed end 17 of the cylinder 7 by means of the straps 18 and 19, respectively.

An axially disposed piston rod guide tube 20 is formed integrally with the closed end 17 of the cylinder 7 and extends vertically above and below said closed end 17, being formed with a vertically extending guide slot or groove 21 for receiving the vertical elongated rib or key 22 formed on the combined piston rod and "Pogo" supporting leg 23.

Below the piston rod and "Pogo" supporting leg 23 and attached to the lower end thereof is an enlarged rubber supporting foot 24 in which a heavy coil spring 25 is embedded or otherwise supported.

A switch arm 26 is mounted upon the side of the piston rod or leg 23, which is prevented from rotation by means of the coacting slot or groove 21 and the key 22 slidably received therein. A cooperating switch or contact finger 27 is supported on the insulated arm 28 secured to the lower end of the guide tube 20, and is connected with the dry cell battery by means of the conductor wire or cable 29.

The piston 30 having a pair of piston rings 31 is supported for vertical reciprocating movement within the cylinder 7 upon the pin 32 extending through the upper and inner end of the piston rod 23, being mounted in the oppositely disposed bearings 33 in the piston 30.

A centrally disposed boss 34 is formed integrally on the upper surface of the piston 30 and supports a heavy coil spring 35 which is adapted to engage the inner surface of the cylinder head 6 when the piston 30 moves upwardly in the cylinder 7, for cushioning the action of the piston and for resiliently projecting the piston downwardly in the cylinder 7 after the combustion charge has been compressed in the upper end of the cylinder 7 and ignited by the spark plug 12.

A deflector rib 36 will be formed integrally with the piston 30 and will extend upwardly from the

3

upper surface thereof adjacent the fuel inlet port 37 formed through the wall of the cylinder 7 at a point approximately midway of its length, whereby the charges of fuel will be deflected to all parts of the cylinder 7 above the piston 30.

A fuel supply tank 38 will be formed about the cylinder 7 being provided with an outwardly and upwardly extending annular wall 39 and a closure top 40 for said tank. The tank 38 will be substantially triangular in cross section and will hold a supply of loosely packed steel wool 41 used for preventing the gasoline when placed in the tank 38 from slushing about, thereby providing a proper and constant feed of fuel to the engine cylinder.

A pipe or tube 42 will be connected at its upper end to the port 43 in the fuel tank 38 and will be connected at its lower end to the port 44 at the lower end of the cylinder 7, whereby the air in the lower part of the cylinder entering through a conventional valved inlet in the wall thereof is compressed as the piston moves downwardly, after which the air is forced through the pipe or tube 42 and into the upper end of the cylinder 7 above the piston 30 to be further compressed and mixed with the fuel and ignited when the switch arm 26 and the switch or contact finger 27 make contact to close the circuit to the battery 16, coil 15 and spark plug 12. As the piston 30 moves downwardly in the cylinder 7, the exhaust gases will be discharged or exhausted through the exhaust port 45 and out from the exhaust pipe 46 connected thereto.

A control switch 47 will be disposed upon the handle 3 and will be connected by means of the electric conductors or wires 48 and 49 to the ignition apparatus of the gasoline engine.

From the foregoing description, it will be apparent that there has been devised and provided a highly efficient form of gasoline engine operated jumping stick which will be highly efficient and amusing in operation, and relatively inexpensive to manufacture and produce, said stick being capable of being operated at various speeds controlled at the will of the operator.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

1. A mechanical jumping stick comprising an upper portion and a lower portion, a hand bar and a foot bar on the opposite ends of said upper portion, a resilient cushioning shoe on the lower end of said lower portion, a gasoline engine disposed between said upper and lower portions and including a cylinder secured to said upper portion, a piston attached to said lower portion and operatively received in said cylinder, guide means for preventing rotary movement between said cylinder and piston, a fuel tank for said engine disposed circumferentially of said cylinder, said cylinder having fuel inlet and exhaust ports through its wall, and ignition means for igniting the fuel in said cylinder when the same has been compressed therein.

4

2. The subject matter as claimed in claim 1, a fuel deflector on said piston, resilient cushioning means on the head of said piston, and a circuit making and breaking mechanism for automatically closing an electric circuit for igniting the fuel in said cylinder when the same has been compressed.

3. The subject matter as claimed in claim 1, a fuel deflector on said piston, resilient cushioning means on the head of said piston, a circuit making and breaking mechanism for automatically closing an electric circuit for igniting the fuel in said cylinder when the same has been compressed, and a control switch on said hand bar for rendering the engine of said pogo stick either operative or inoperative.

4. A mechanical jumping stick comprising a cylinder defining a body section, a rigid upper structure extending upwardly from said cylinder, and including vertically spaced hand and foot bars, a reciprocating lower structure operatively extending from the lower end of the cylinder and including a piston rod having a resilient cushioning element disposed on its outer end, a piston slidably mounted in said cylinder and connected to the inner end of the piston rod, guide means for preventing rotary movement between said cylinder and piston, a fuel tank disposed circumferentially of said cylinder, said cylinder having fuel inlet and exhaust ports through its wall, and ignition means for igniting the fuel in said cylinder and control means responsive to the sequential reciprocation of the piston rod in the cylinder for said ignition means.

5. The combination of claim 4, wherein said guide means includes an elongated key formed in said piston rod and a complementary groove formed in the lower end of the cylinder.

6. The combination of claim 4, wherein resilient means is disposed in the cylinder between the upper end thereof and the piston for cushioning the action of the piston and urging the same downwardly in the cylinder.

7. The combination of claim 4, wherein said control means for the ignition means includes a source of electrical energy carried by the cylinder, a switch interposed between said source and the ignition means.

8. The combination of claim 7, wherein said switch includes a fixed positive contact carried by the lower end of the cylinder and a movable ground contact secured to the piston rod adjacent the outer end thereof.

RICHARD J. MAYS.
